METHOD OF FORMING FOUNDATION
PILES

Elihu D. Watt, Plainfield, N. J., assignor to Raymond Concrete Pile Company, New York, N. Y., a corporation of New Jersey

Application March 9, 1935, Serial No. 10,132

2 Claims. (Cl. 61—57)

This invention pertains to a method of forming foundation piles, each pile comprising a steel beam, or the like, with its upper end encased in concrete. The beam may be a structural shape, or tubular, or may even be of wood, and plastic material such as asphalt or tar may be used in place of concrete.

The method herein disclosed has the advantage of low cost and convenience, since the whole operation is performed right on the job, no special apparatus being required.

This method also has the advantage of improving the quality of the concrete, its density being increased by the vibratory effect of the beam during driving and by compression due to displacement by the beam passing through it, vibration and compression being well-known means of increasing density. Thus the protective properties of the concrete are increased.

Further and other objects and advantages will be apparent from the specification and claims, and from the accompanying drawings which illustrate what is now considered the preferred embodiment of the invention.

In the drawings:

Fig. 1 shows a hole bored in the ground to serve as a mold for the plastic material.

Fig. 2 shows the hole of Fig. 1 filled with plastic material.

Fig. 3 shows the finished pile, a steel beam having been driven through the plastic mass to footing.

Fig. 4 is a plan view of Fig. 3.

Fig. 5 shows the first step of the method when the ground is of such nature as to require a lining in the mold to prevent collapse of the walls of the mold.

Fig. 6 shows the casing of Fig. 5 filled with plastic material after removal of the driving core.

Fig. 7 shows the steel beam, casing and plastic material after driving of the beam.

Fig. 8 shows the finished structure, the casing having been removed.

In Fig. 1, 10 designates a hole bored by an auger or otherwise in ground 12 which is firm enough so that the wall of the hole is self-sustaining. Fig. 2 shows hole (mold) 10 filled with plastic material, usually concrete, 14, and Fig. 3 shows the finished structure, the beam 16 having been

forced downwardly through mass 14 to rock or other footing 18, after which, if the material is concrete it is allowed to set. If water rises in the hole (Fig. 1) the concrete (Fig. 2) may be placed by tremie until above water level.

If the ground is not self-sustaining the mold 10 may be formed by sinking into the ground a casing 20 mounted on a drive core 22 (Fig. 5). After the core is removed casing 20 is filled with plastic concrete 24 (Fig. 6) after which casing 20 is removed and beam 16 is driven through the concrete as before (Fig. 3). If the soil be watery, casing 20 may be provided with a boot at its lower end and after sealing with concrete the beam may be driven.

Of course various modifications of the above method will occur to those skilled in the art. For instance, as in Figs. 6 and 7, the beam may be driven before casing 20 is removed, or while the mold is only partly filled with concrete, the balance of the concrete being poured after the driving, or casing 20 may be withdrawn during or after the concrete pouring operation, thus forming the condition of Fig. 2, after which the beam is driven as in Fig. 3. Also in the hole of Fig. 1, 25 a permanent shell as indicated by dotted lines 26 may be used to keep the concrete out of contact with the ground. The beam may even be encased throughout its length.

It is to be understood that the invention is not limited to the specific embodiment herein illustrated and described but may be used in other ways without departure from its spirit as defined by the following claims.

I claim:

1. In the method of forming a pile, the steps of providing a mass of plastic concrete, forcing a beam lengthwise through said mass until a portion of said beam projects below said mass and letting said concrete set around said beam.

2. In the method of forming a pile, the steps of providing a mass of plastic concrete near ground level, driving a beam lengthwise through said concrete to footing a substantial distance below ground level and letting said concrete set around the upper end of said pile.

ELIHU D. WATT.
